R. SUCZEK

EJECTOR SYSTEM

Filed March 31, 1922

UNITED STATES PATENT OFFICE.

ROBERT SUCZEK, OF PHILADELPHIA, PENNSYLVANIA, ASSIGNOR TO C. H. WHEELER MANUFACTURING COMPANY, OF PHILADELPHIA, PENNSYLVANIA, A CORPORATION OF PENNSYLVANIA.

EJECTOR SYSTEM.

Application filed March 31, 1922. Serial No. 548,369.

To all whom it may concern:

Be it known that I, ROBERT SUCZEK, a citizen of the United States, residing in the city and county of Philadelphia, State of Pennsylvania, have invented certain new and useful Improvements in Ejector Systems, of which the following is a specification.

My invention relates to a system involving the employment of ejectors for compressing or raising the pressure of elastic fluid from any suitable or desirable pressure to a higher pressure, and more particularly from a pressure below that of the atmosphere to any other suitable pressure, as atmospheric pressure, or greater or less than atmospheric pressure.

In accordance with my invention, heat is abstracted from the ejector motive fluid, as steam, when of too high or excessive pressure or when superheated, or both, and the heat so abstracted is usefully applied, and the motive fluid or steam, after reduction of its pressure, or superheat, or both, is still fully effective from the viewpoint of ejector operation.

Further in accordance with my invention, the heat abstracted from the ejector motive fluid before delivery to the nozzle structure of the ejector apparatus is employed for any suitable or desired purpose, as for elevation of temperature of gases, vapors or liquids, but is mainly or preferably employed in generating low pressure steam to be utilized as motive fluid of ejector apparatus, more particularly as the motive fluid of an ejector augmentor preferably associated or co-operating with the aforesaid ejector apparatus.

Further in accordance with my invention the aforesaid ejector system is employed for producing or maintaining a vacuum in a condenser of a steam power plant in which is condensed the steam exhausted from a turbine or other steam-driven motor or engine, and the condensate, preferably after it has been utilized as the cooling medium of the condenser structure or structures into which one or more of the ejectors discharges, is raised in temperature, preferably for boiler feed purposes, by heat extracted from the aforesaid high pressure or superheated motive fluid or steam; and preferably, it is a part of such condensate which is

evaporated into low pressure steam for ejector motive fluid.

My invention resides in the method, apparatus and system hereinafter described.

For an understanding of my system, method and apparatus, reference is to be had to the accompanying drawing, which is an elevational view, some parts in section, of one of various forms my system or apparatus may take.

Referring to the drawing, C is a condenser, which may be of the jet or any other suitable type, but in the example illustrated is a surface condenser having the port A through which steam or other condensable fluid, as exhaust steam from a power plant turbine or engine, is delivered into the condenser C between the condenser tubes c, only a few of which are indicated, through which passes cooling water, as well understood in the condenser art. From suitable region 75 within the condenser C, as from beneath or behind the baffle b, air and other uncondensed or uncondensable fluid is withdrawn by the ejector E, of any suitable type, which may be an augmentor, having nozzle structure N for 80 expanding elastic motive fluid. The mixture of motive fluid and air or other fluid withdrawn from the condenser C for producing or maintaining a vacuum therein, is discharged into a condenser K, of any suitable type, here indicated as a surface condenser, in which is condensed the motive fluid of the ejector E, the condensate being delivered to any suitable region, as for example, to the hot well H of the condenser 85 C through the pipe a controlled by the valve d. The air and other uncondensed fluid are withdrawn from the condenser K by the ejector E¹ having nozzle structure N¹ by the ejector E¹ having nozzle structure N¹ which expands elastic motive fluid, and the mixture of motive and entrained fluids is 90 discharged into the condenser K¹, of any suitable type, here indicated as a surface condenser, in which the motive fluid of the ejector E¹ is condensed, the condensate being delivered to any suitable region, as to the hot well H through pipe e controlled by the valve f. The uncondensed fluid is withdrawn from the condenser K¹ by the ejector E², of any suitable type, but here indicated 95 as of the type disclosed in Letters Patent of the United States No. 1,282,595. The mixture of motive and entrained fluids dis-

charged from the ejector E^2 into the condenser K^2 , of any suitable type, here indicated as a surface condenser, in which the motive fluid from the ejector E^2 is condensed, the condensate being delivered to any suitable point, as the hot well H , or as indicated, through pipe g controlled by valve h and the pipe B to which, if desired, the condensate from one or more of the condensers K and K^1 may be conducted.

While it is preferred to employ the three condensers K , K^1 and K^2 as described, it shall be understood that my invention is not limited thereto, but that any one or more or all of them may be omitted.

It will further be understood that either or both of the ejectors E , E^1 may be of the radial flow type disclosed in said prior Letters Patent of the United States No. 1,282,595; and it will further be understood that the ejector E^2 may be of a tubular type similar to E or E^1 .

The cooling medium for the condensers K , K^1 and K^2 may be anything suitable or desirable, it being understood that one or more of these condensers may have cooling medium derived from one source, and one or more of them from any other source.

In the example illustrated, however, and preferably, the cooling medium for these condensers is the condensate from the condenser C . The condensate removal pump P is driven by any suitable motor M , as an electric motor, steam engine or turbine. The condensate traverses the cooling systems of the condensers K , K^1 and K^2 in series or tandem, though the system of piping may be arranged in any other suitable or desired way.

S is a heater or evaporator having a chamber D above the tube sheet i , a chamber F below the tube sheet j and a chamber G between the tube sheets i and j . Tubes k , of suitable number, terminate in the tube sheets i and j and connect the chambers D and F . The chambers D and F are also connected by pipe or conduit m , in which is disposed the valve member n controlled by the float o in the chamber G .

The condensate from the condenser C is delivered into the chamber D through the spray nozzle, rose or equivalent device I . There is also delivered into the chamber D through the pipe B condensate from one or more of the condensers K , K^1 or K^2 , as aforesaid, and also, and preferably, make-up water for addition to the condensate delivered to the chamber D through the device I , to serve preferably as the feed water for the steam generators or boilers of the steam plant of which the condenser C and auxiliaries are a part.

The liquids delivered into the chamber D have their temperature raised therein by any suitable heating medium which may be

introduced through the port J , this heating medium being, for example, exhaust steam from the engine or turbine M , or from any other source, the heating medium coming into direct contact with the liquid and raising it to a temperature to or near the boiling point. The port L is a vent to atmosphere or means of connection of the chamber D to any other chamber under any suitable or desired pressure. The port O is connected by suitable piping, not shown, to a boiler feed pump for feeding the heated water directly to a steam boiler or boilers, or through intermediate economizers or other heat transfer structures or other devices, as may be suitable or desirable in power plant practice.

Through the pipe Q is delivered live or high pressure steam, as for example, of a pressure of seventy pounds or upwardly to two hundred or three hundred pounds, or more, derived from any source, as the boiler which delivers steam to the turbine or engine which exhausts into the condenser C . The pipe Q delivers the steam through pipe p and valves q and r to the nozzle structure N^1 of the ejector E^1 and to the nozzle structure of the ejector E^2 .

For economic operation of the ejectors E^1 and E^2 , or either of them, from the standpoint of steam or motive fluid consumption, excess pressure is unnecessary and wasteful, as may also be any superheat of the steam delivered by the pipe Q . The heat units represented by excess pressure, or by superheat, or by both, are not economically availed of in the ejector apparatus. The heat units representing excess pressure or superheat, or both, are more or less completely abstracted from the steam delivered by the pipe Q before reaching the nozzle structures of either or both of the ejectors E^1 and E^2 , abstraction of heat serving to reduce the pressure of the steam and also to reduce or completely remove the superheat, or both.

The abstraction of heat is effected by any suitable heat transfer structure, as the pipe coil R , disposed in the chamber G of the heater or evaporator S , atmospheric pressure, or preferably less than atmospheric pressure, obtaining in the chamber G . Heat is transferred by the hot water in the tubes k through the walls of those tubes to the water in the chamber G , and additional heat is transferred to the water in the chamber G from the pipe coil R , the heat applied to the water in the chamber G causing it to boil or vaporize and produce low pressure steam, as of a pressure preferably somewhat below atmospheric pressure. As the water in the chamber G is evaporated and delivered to the pipe s , the float o descends and admits water into chamber G from the chamber D , the float controlled valve n

maintaining the level of water in the chamber G approximately constant. The heat delivered to the water or steam in the chamber G by the pipe coil R reduces the pressure or superheat, or both, of the steam delivered by the pipe Q, and the heat of the steam generated in the chamber G is due mainly or principally to the heat in the condensate or water in the chamber D and to the heat abstracted from the steam delivered by the pipe Q.

The low pressure steam generated in chamber G is conducted through the pipe s, controlled by valves t and u, between which the pipe v controlled by valve w may deliver high pressure steam, when suitable or desirable, upon closure of the valve t. The pipe s delivers steam to the nozzle structure N of the augmentor ejector E, while the steam leaving the pipe coil R with reduced pressure or reduced superheat, or both, is delivered to the nozzle structures of the ejectors E¹, E², such steam being nevertheless relatively high pressure or live steam, having a pressure, for example, of seventy to one hundred and fifty pounds per square inch, more or less, and suited for economical operation of the ejectors E¹ and E², the excess heat units, represented by excess pressure or superheat, or both, and which would be of little or no benefit in operation of the ejectors E¹ and E², having been abstracted and employed, at least in part, for production of low pressure steam for the ejector E.

The ejector E raises the pressure of the air and other uncondensed elastic fluid removed from the condenser C, in which a vacuum of the order of twenty-eight or twenty-nine inches of mercury is produced or maintained, to suitably higher pressure, as for example, from one and one-half times to three or four times, more or less, the absolute pressure in the condenser C. The steam or motive fluid from the ejector E is condensed in the condenser K, and the air and other uncondensed fluid are then further raised in pressure by ejectors E¹ and E², the air and uncondensed elastic fluid being finally discharged from the condenser K² at z, to atmosphere or to any other desired region at any suitable pressure, as atmospheric pressure, or a pressure above or below atmospheric.

The ratio of compression of the ejector E may be anything suitable or desirable, and may be, as aforesaid, from about one and one-half to three or four; and the relation of the ratios of compression of the ejectors E¹ and E² may be made anything suitable or desirable, and may be that described in Letters Patent of the United States No. 1,283,593.

By the method and apparatus described, the motive fluid for the ejector E is econom-

ically procured by utilizing heat of the feed water or condensate in chamber D and the heat in the steam for the ejectors E and E², or either of them, which would otherwise not be efficiently employed in operating them; and there is a further economy in that the amount of motive fluid required for the ejectors E¹ and E², or either of them, is materially reduced, from the fact that the augmentor E performs a substantial portion of the entire work of compressing the air and other uncondensable elastic fluid from the condenser C to atmospheric or other pressure.

While the ejector or augmentor E, employing the low pressure steam, is preferably employed to effect the first stage of compression, it will be understood that it may be used in any other position in a later stage of a series of one or more ejectors.

It will be further understood that the ejector E² may be omitted or supplanted by any other type of air pump, as a mechanical air pump; or both ejectors E¹ and E² may be supplanted by another type of air pump or pumps, as a mechanical air pump or pumps.

For the sake of brevity in the appended claims, the term "steam" includes steam and any equivalent elastic fluid, and the term "air" includes air and other uncondensed or uncondensable elastic fluid.

What I claim is:

1. The method which comprises abstracting heat from live steam having excess pressure or superheat, or both, thereafter expanding the live steam of reduced pressure or superheat, or both, into a jet, entraining air by the jet, converting the velocity of the mixture of air and steam into pressure, and utilizing the abstracted heat.

2. The method which comprises transferring heat from steam having excess pressure or superheat, or both, to a liquid to produce low pressure steam, expanding the low pressure steam into a jet, entraining air by said jet, and converting the velocity of the air and steam into pressure.

3. The method which comprises abstracting heat from steam having excess pressure or superheat, or both, and thereafter expanding the steam into a jet, entraining air by the jet, converting the velocity of the mixture of air and steam into pressure, and absorbing the abstracted heat by a liquid.

4. The method which comprises abstracting heat from steam having excess pressure or superheat, or both, and thereafter expanding the steam into a jet, entraining air by the jet, converting the velocity of the mixture of air and steam into pressure, and absorbing the abstracted heat by a liquid for the production of steam.

5. The method which comprises abstract-

ing heat from steam having excess pressure or superheat, or both, and thereafter expanding the steam into a jet, entraining air by the jet, converting the velocity of the 5 mixture of air and steam into pressure, and absorbing the abstracted heat in the production of low pressure steam, expanding the low pressure steam into a second jet, entraining air by said second jet, and converting 10 the velocity of the mixture into pressure.

6. The method which comprises transferring heat from steam having excess pressure or superheat, or both, to a liquid 15 to produce low pressure steam, expanding the low pressure steam into a jet, entraining air by said jet, converting the velocity of the air and steam into pressure, and ejecting the air so raised in pressure to higher 20 pressure by expansion of said steam from which heat has been abstracted.

7. The method which comprises transferring heat from steam having superheat or excess pressure, or both, to low pressure 25 steam, expanding the low pressure steam into a jet, entraining air by the jet, and converting the velocity of the mixture into pressure.

8. The method which comprises producing 30 low pressure steam whose heat is derived in part from heated liquid and in part by heat abstracted from steam having superheat or excess pressure, or both, and ejecting air by the low pressure steam to higher pressure.

35 9. The method which comprises producing low pressure steam whose heat is derived in part from heated liquid delivered to a region of lower pressure at which it vaporizes and in part by heat abstracted from 40 steam having superheat or excess pressure, or both, and ejecting air by the low pressure steam to higher pressure.

10. The method which comprises producing 45 low pressure steam whose heat is derived in part from heated liquid and in part by heat abstracted from steam having superheat or excess pressure, or both, ejecting air by the low pressure steam to higher pressure, and utilizing the steam from which 50 heat has been abstracted for ejecting air to higher pressure.

11. The method which comprises producing 55 low pressure steam whose heat is derived in part from heated liquid and in part by heat abstracted from steam having superheat or excess pressure, or both, ejecting air by the low pressure steam to higher pressure, and utilizing the steam from which 60 heat has been abstracted for ejecting said air to still higher pressure.

12. The method which comprises producing 65 low pressure steam whose heat is derived in part from heated liquid delivered to a region of lower pressure at which it vaporizes and in part by heat abstracted

from steam having superheat or excess pressure, or both, ejecting air by the low pressure steam to higher pressure, and utilizing the steam from which heat has been abstracted for ejecting air to higher 70 pressure.

13. The method which comprises producing low pressure steam whose heat is derived in part from heated liquid delivered to a region of lower pressure at which it 75 vaporizes and in part by heat abstracted from steam having superheat or excess pressure, or both, ejecting air by the low pressure steam to higher pressure, and utilizing the steam from which heat has been abstracted for ejecting said air to still 80 higher pressure.

14. The method which comprises condensing steam, vaporizing the condensate into low pressure steam whose heat is at 85 least in part the heat abstracted from steam having superheat or excess pressure, or both, and ejecting to higher pressure air by said low pressure steam from the space in which said 90 first named steam is condensed.

15. The method which comprises condensing steam, vaporizing the condensate into low pressure steam whose heat is at least in part the heat abstracted from steam having superheat or excess pressure, or both, 95 ejecting to higher pressure air by said low pressure steam from the space in which said first named steam is condensed, and ejecting said air to still higher pressure by said steam from which heat has been abstracted. 100

16. The method which comprises condensing steam, transferring heat to the condensate to raise its temperature, transferring the heated condensate to a region of lower pressure for production of low 105 pressure steam at least a part of whose heat is abstracted from steam having superheat or excess pressure, or both, and ejecting air by said low pressure steam from the space in which said first named steam is condensed 110 to higher pressure.

17. The method which comprises condensing steam, transferring heat to the condensate to raise its temperature, transferring the heated condensate to a region 115 of lower pressure for production of low pressure steam at least a part of whose heat is abstracted from steam having superheat or excess pressure, or both, and ejecting air derived from the space in which said first named steam is condensed to higher pressure 120 by said steam from which heat has been abstracted.

18. The method which comprises condensing steam, transferring heat to the condensate to raise its temperature, transferring the heated condensate to a region of lower pressure for production of low pressure steam at least a part of whose heat is abstracted from steam having superheat or 125 130

- excess pressure, or both, ejecting air by said low pressure steam from the space in which said first named steam is condensed to higher pressure, and further raising the pressure of 5 said air by ejecting it by said steam from which heat has been abstracted.
19. The combination with an ejector, of a source of live steam, and means intermediate said source and the nozzle structure of said 10 ejector for abstracting and utilizing heat from the steam to effect live motive steam for said ejector.
20. The combination with an ejector, of a source of superheated steam, a connection 15 from said source to the nozzle structure of said ejector, and means in said connection for abstracting heat from the steam to reduce its superheat.
21. The combination with an ejector, of a source of live steam, a connection between 20 said source and the nozzle structure of said ejector, and means for reducing the pressure of said steam before reaching said nozzle structure comprising means in said connection 25 for abstracting and utilizing heat from the steam to effect live motive steam for said ejector.
22. The combination with an ejector, of a source of live steam having superheat and 30 excess pressure, a connection from said source to the nozzle structure of said ejector, and means in said connection for abstracting heat from the steam at a rate to reduce its superheat and pressure to effect live 35 motive steam for said ejector.
23. The combination with an ejector, of a source of low pressure steam connected with the nozzle structure thereof and comprising means for heating a liquid, a source of 40 steam, and heat transfer structure traversed by steam from said source for imparting additional heat to said liquid.
24. The combination with an ejector, of a source of low pressure steam connected with 45 the nozzle structure thereof and comprising means for heating a liquid, a source of steam, heat transfer structure traversed by steam from said source for imparting additional heat to said liquid, a second ejector, and means for conducting steam from said 50 heat transfer structure to the nozzle structure of said second ejector.
25. The combination with an ejector, of a source of low pressure steam connected with 55 the nozzle structure thereof and comprising means for heating a liquid, a source of steam, heat transfer structure traversed by steam from said source for imparting additional heat to said liquid, a second ejector, and means for conducting steam from said 60 heat transfer structure to the nozzle structure of said second ejector, and means for connecting said ejectors in series.
26. The combination with an ejector, of a source of low pressure steam connected with 65
- the nozzle structure thereof and comprising means for heating a liquid, a source of steam, heat transfer structure traversed by steam from said source for imparting additional heat to said liquid, a second ejector, means for conducting steam from said heat transfer structure to the nozzle structure of said second ejector, and means for connecting said ejectors in series.
27. The combination with an ejector, of a source of low pressure steam connected with the nozzle structure thereof, means for imparting heat to said low pressure steam comprising heat transfer structure, and means 80 for delivering steam to said structure.
28. The combination with an ejector, of a source of low pressure steam connected with the nozzle structure thereof, means for imparting heat to said low pressure steam comprising heat transfer structure, a second ejector, and means for delivering steam to the nozzle structure of said second ejector through said heat transfer structure.
29. The combination with an ejector, of a source of low pressure steam connected with the nozzle structure thereof, means for imparting heat to said low pressure steam comprising heat transfer structure, a second ejector, means for delivering steam to the 90 nozzle structure of said second ejector through said heat transfer structure, and means connecting said ejectors in series.
30. The combination with an ejector, of a source of low pressure steam connected with the nozzle structure thereof, means for imparting heat to said low pressure steam comprising heat transfer structure, a second ejector, means for delivering steam to the 95 nozzle structure of said second ejector through said heat transfer structure, and means for connecting the discharge of said first named ejector to the suction of said second named ejector.
31. The combination with a plurality of 100 ejectors, of sources of high and low pressure steam connected, respectively, to the nozzle structures of said ejectors, and means for extracting heat from the high pressure steam and delivering it to the low pressure 105 steam.
32. The combination with a plurality of 110 ejectors, of sources of high and low pressure steam connected, respectively, to the nozzle structures of said ejectors, means for extracting heat from the high pressure steam and delivering it to the low pressure steam, and means for connecting said 115 ejectors in series.
33. The combination with a plurality of 120 ejectors, of sources of high and low pressure steam connected, respectively, to the nozzle structures of said ejectors, means for extracting heat from the high pressure steam and delivering it to the low pressure steam, and means for connecting said 125 ejectors in series.
34. The combination with a plurality of 130 ejectors, of sources of high and low pressure steam connected, respectively, to the nozzle structures of said ejectors, means for extracting heat from the high pressure steam and delivering it to the low pressure steam,

and means for connecting the discharge of an ejector operated by low pressure steam to the suction of an ejector operated by high pressure steam.

5 34. The combination with a plurality of
ejectors, of sources of high and low pressure
steam connected, respectively, to the nozzle
structures of said ejectors, means for ex-
tracting heat from the high pressure steam
10 and delivering it to the low pressure steam,
means for connecting said ejectors in series,
a condenser between said ejectors, and means
for delivering condensate from said con-
denser to said source of low pressure steam.

15 35. The combination with a plurality of ejectors, of sources of high and low pressure steam connected, respectively, to the nozzle structures of said ejectors, means for extracting heat from the high pressure steam and delivering it to the low pressure steam, means for connecting the discharge of an ejector operated by low pressure steam to the suction of an ejector operated by high pressure steam, a condenser between said ejectors, and means for delivering condensate from said condenser to said source of low pressure steam.

20

25

36. The combination with an evaporating chamber, of a source of steam, an ejector, a connection from said source to the nozzle structure of said ejector, and structure in said connection disposed in said chamber for transferring heat from steam from said source into said chamber.

35 37. The combination with an evaporating chamber, of a source of steam, an ejector, a connection from said source to the nozzle structure of said ejector, structure in said connection disposed in said chamber for
40 transferring heat from steam from said source into said chamber, and a second heat transfer structure in said chamber.

45 38. The combination with an evaporating chamber, of a source of steam, an ejector, a connection from said source to the nozzle structure of said ejector, structure in said connection disposed in said chamber for transferring heat from steam from said source into said chamber, a second heat transfer structure in said chamber, and a liquid heating chamber communicating with said second heat transfer structure.

55 39. The combination with an evaporating chamber, of a source of steam, an ejector, a connection from said source to the nozzle structure of said ejector, structure in said connection disposed in said chamber for transferring heat from steam from said source into said chamber, a second heat transfer structure in said chamber, a liquid heating chamber communicating with said second heat transfer structure, and means for conducting a portion of the liquid from said heating chamber into said evaporating chamber.

60

65

40. The combination with an evaporating chamber, of a source of steam, an ejector, a connection from said source to the nozzle structure of said ejector, structure in said connection disposed in said chamber for transferring heat from steam from said source into said chamber, a second heat transfer structure in said chamber, a liquid heating chamber communicating with said second heat transfer structure, means for conducting a portion of the liquid from said heating chamber into said evaporating chamber, the pressure in said evaporating chamber being lower than in said liquid heating chamber.

41. The combination with an evaporating chamber, of a source of steam, an ejector, a connection from said source to the nozzle structure of said ejector, structure in said connection disposed in said chamber for transferring heat from steam from said source into said chamber, and a second ejector whose nozzle structure is connected to said evaporating chamber.

42. The combination with an evaporating chamber, of a source of steam, an ejector, a connection from said source to the nozzle structure of said ejector, structure in said connection disposed in said chamber for transferring heat from steam from said source into said chamber, a second heat transfer structure in said chamber, and a second ejector whose nozzle structure is connected to said evaporating chamber. 90
95

43. The combination with an evaporating chamber, of a source of steam, an ejector, a connection from said source to the nozzle structure of said ejector, structure in said connection disposed in said chamber for transferring heat from steam from said source into said chamber, a second heat transfer structure in said chamber, a liquid heating chamber communicating with said second heat transfer structure, and a second ejector whose nozzle structure is connected to said evaporating chamber. 100
105
110

44. The combination with an evaporating chamber, of a source of steam, an ejector, a connection from said source to the nozzle structure of said ejector, structure in said connection disposed in said chamber for transferring heat from steam from said source into said chamber, a second heat transfer structure in said chamber, a liquid heating chamber communicating with said second heat transfer structure, means for conducting a portion of the liquid from said heating chamber into said evaporating chamber, and a second ejector whose nozzle structure is connected to said evaporating chamber.

45. The combination with an evaporating chamber, of a source of steam, an ejector, a connection from said source to the nozzle structure of said ejector, structure in said 130

connection disposed in said chamber for transferring heat from steam from said source into said chamber, a second heat transfer structure in said chamber, a liquid heating chamber communicating with said second heat transfer structure, means for conducting a portion of the liquid from said heating chamber into said evaporating chamber, the pressure in said evaporating chamber being lower than in said liquid heating chamber, and a second ejector whose nozzle structure is connected to said evaporating chamber.

46. The combination with an evaporating chamber, of a source of steam, an ejector, a connection with said source to the nozzle structure of said ejector, structure in said connection disposed in said chamber for transferring heat from steam from said

20 source into said chamber, a second ejector whose discharge communicates with the suction of said first named ejector, and means connecting said evaporating chamber with the nozzle structure of said second ejector.

25 47. The combination with an evaporating chamber, of a source of steam, an ejector, a connection from said source to the nozzle structure of said ejector, structure in said connection disposed in said chamber for 30 transferring heat from steam from said source into said chamber, a second heat transfer structure in said chamber, a second ejector whose discharge communicates with the suction of said first named ejector, and means connecting said evaporating chamber with the nozzle structure of said second ejector.

40 48. The combination with an evaporating chamber, of a source of steam, an ejector, a connection from said source to the nozzle structure of said ejector, structure in said connection disposed in said chamber for transferring heat from steam from said source into said chamber, a second heat transfer structure in said chamber, a liquid heating chamber communicating with said second heat transfer structure, a second ejector whose discharge communicates with the suction of said first named ejector, and means connecting said evaporating chamber with the nozzle structure of said second ejector.

55 49. The combination with a condenser, of a source of low pressure steam, means for delivering condensate from said condenser to said source, an ejector for removing air from said condenser, a connection from the nozzle structure of said ejector to said source, a second source of steam, a second ejector, a connection from said second source of steam to the nozzle structure of said second ejector, heat transfer structure in said connection for delivering heat to said source of low pressure steam.

60 50. The combination with a condenser, of a source of low pressure steam, means for delivering condensate from said condenser to said source, an ejector for removing air from said condenser, a connection from the nozzle structure of said ejector to said source, a second source of steam, a second ejector, a connection from said second source of steam to the nozzle structure of said second ejector, heat transfer structure in said connection for delivering heat to said source of low pressure steam.

a source of low pressure steam, means for delivering condensate from said condenser to said source, an ejector for removing air from said condenser, a connection from the nozzle structure of said ejector to said source, a second source of steam, a second ejector, a connection from said second source of steam to the nozzle structure of said second ejector, heat transfer structure in said connection for delivering heat to said source of low pressure steam, a condenser through which one of said ejectors is connected to the other, and means for conducting said condensate of said first condenser through the cooling system of said second condenser in advance of delivery to said source of low pressure steam.

51. The combination with a condenser, of a source of low pressure steam, means for delivering condensate from said condenser to said source, an ejector for removing air from said condenser, a connection from the nozzle structure of said ejector to said source, a second source of steam, a second ejector, a connection from said second source of steam to the nozzle structure of said second ejector, heat transfer structure in said connection for delivering heat to said source of low pressure steam, means for connecting said ejectors in series, a condenser into which the later stage ejector discharges, and means for conducting said condensate of said first named condenser through the cooling system of said second condenser in advance of delivery to said source of low pressure steam.

52. The combination with a condenser, of a source of low pressure steam, means for delivering condensate from said condenser to said source, an ejector for removing air from said condenser, a connection from the nozzle structure of said ejector to said source, a second source of steam, a second ejector, a connection from said second source of steam to the nozzle structure of said second ejector, heat transfer structure in said connection for delivering heat to said source of low pressure steam, and a third ejector whose nozzle structure receives steam through said heat transfer structure.

53. The combination with a condenser, of a source of low pressure steam, means for delivering condensate from said condenser to said source, an ejector for removing air from said condenser, a connection from the nozzle structure of said ejector to said source, a second source of steam, a second ejector, a connection from said second source of steam to the nozzle structure of said second ejector, heat transfer structure in said connection for delivering heat to said source of low pressure steam, a third ejector whose nozzle structure receives steam through said heat transfer structure, a condenser into which said third ejector discharges, and means for conducting said condensate from

said first condenser through the cooling system of said second condenser in advance of delivery to said source of low pressure steam.

54. The combination with a condenser, of 5 ejectors employing, respectively, high and low pressure steam as motive fluid for removing air from said condenser, a heater, means for delivering condensate from said condenser to said heater, an evaporator producing 10 low pressure steam heated by the hot condensate, a connection from said evaporator to the nozzle structure of one of said ejectors, a source of high pressure steam, a connection therefrom to the nozzle 15 structure of another of said ejectors, and heat transfer structure in said connection disposed in said evaporator.

55. The combination with a condenser, of 20 ejectors employing, respectively, high and low pressure steam as motive fluid for removing air from said condenser, a heater, means for delivering condensate from said condenser to said heater, an evaporator producing low pressure steam heated by the hot 25 condensate, means for delivering a part of the heated condensate to said evaporator, a connection from said evaporator to the nozzle structure of one of said ejectors, a source of high pressure steam, a connection 30 therefrom to the nozzle structure of another of said ejectors, and heat transfer structure in said connection disposed in said evaporator.

56. The combination with a condenser, of 35 ejectors employing, respectively, high and low pressure steam as motive fluid for removing air from said condenser, a heater, means for delivering condensate from said condenser to said heater, an evaporator producing 40 low pressure steam heated by the hot condensate, a connection from said evaporator to the nozzle structure of one of said ejectors, a source of high pressure steam, a connection therefrom to the nozzle 45 structure of another of said ejectors, heat transfer structure in said connection disposed in said connection disposed in said evaporator, condensing means associated with said ejectors, and means for passing said condensate of said condenser through the cooling system of said condenser in advance of delivery to said heater.

57. The combination with a condenser, of 55 ejectors employing, respectively, high and low pressure steam as motive fluid for removing air from said condenser, a heater, means for delivering condensate from said condenser to said heater, an evaporator producing low pressure steam heated by the 60 hot condensate, means for delivering a part of the heated condensate to said evaporator, a connection from said evaporator to the nozzle structure of one of said ejectors, a source of high pressure steam, a connection 65 therefrom to the nozzle structure of an-

other of said ejectors, heat transfer structure in said connection disposed in said evaporator, condensing means associated with said ejectors, and means for passing said condensate of said condenser through 70 the cooling system of said condenser in advance of delivery to said heater.

58. The combination with ejectors operated, respectively, by high and low pressure steam as motive fluid, of a heater having 75 a plurality of chambers, an evaporating chamber between said chambers, tubes passing through said evaporating chamber and connecting said chambers of said heater, a connection from said evaporating chamber 80 to the nozzle structure of one of said ejectors, a source of high pressure steam, a connection therefrom to the nozzle structure of another of said ejectors, and heat transfer structure in said connection and disposed 85 in said evaporating chamber.

59. The combination with ejectors operated, respectively, by high and low pressure steam as motive fluid, of a heater having 90 a plurality of chambers, an evaporating chamber between said chambers, tubes passing through said evaporating chamber and connecting said chambers of said heater, a connection from said evaporating chamber 95 to the nozzle structure of one of said ejectors, a source of high pressure steam, a connection therefrom to the nozzle structure of another of said ejectors, heat transfer structure in said connection and disposed in said 100 evaporating chamber, and means delivering liquid from one of said heater chambers to said evaporating chamber in accord with the amount of low pressure steam delivered to said one of said ejectors.

60. The method which consists in delivering water to a region having a pressure below atmospheric pressure to convert it into low pressure steam, expanding said low pressure steam into a jet, and entraining fluid by said jet and raising it to higher pressure.

61. The method which consists in delivering water to a region having a pressure below atmospheric pressure, adding heat thereto while in said region to produce low pressure steam, expanding said low pressure steam into a jet, and entraining fluid by said jet and raising it to higher pressure.

62. The method which consists in delivering a portion of a body of water into a region having a pressure below atmospheric pressure, transferring heat from said body of water to said water in said region to convert the same into low pressure steam, expanding said low pressure steam into a jet, and entraining fluid by said jet and raising it to higher pressure.

63. The method which consists in delivering water to a region having a pressure below atmospheric pressure to convert it into

low pressure steam, expanding said low pressure steam into a jet, entraining fluid by said jet and raising it to higher pressure, and thereafter extracting heat from said steam to increase the heat content of said water before its delivery to said region.

64. The method which consists in delivering water to a region having a pressure below atmospheric pressure, adding heat thereto while in said region to produce low pressure steam, expanding said low pressure steam into a jet, entraining fluid by said jet and raising it to higher pressure, and thereafter extracting heat from said steam to increase the heat content of said water before its delivery to said region.

65. The method which consists in delivering a portion of a body of water into a region having a pressure below atmospheric pressure, transferring heat from said body of water to said water in said region to convert the same into low pressure steam, expanding said low pressure steam into a jet, entraining fluid by said jet and raising it to higher pressure, and thereafter extracting heat from said steam to increase the heat content of said water.

66. The combination with a chamber within which there exists a pressure below atmospheric pressure, of means for delivering water thereto for the production of low pressure steam, an ejector, and a connection from said chamber to the nozzle structure of said ejector.

67. The combination with a chamber within which there exists a pressure below atmospheric pressure, of means for delivering water thereto, means for adding heat to the water in said chamber in the production of low pressure steam, an ejector, and a connection from said chamber to the nozzle structure of said ejector.

68. The combination with a chamber within which there exists a pressure below atmospheric pressure, of a body of water, means for delivering water from said body into said chamber, means for transferring heat from said body to the water in said chamber in the production of low pressure

steam, an ejector, and a connection from said chamber to the nozzle structure of said ejector.

69. The combination with a chamber within which there exists a pressure below atmospheric pressure, of means for delivering water thereto for the production of low pressure steam, an ejector, a connection from said chamber to the nozzle structure of said ejector, and means for transferring heat from the fluid discharged by said ejector to said water.

70. The combination with a chamber within which there exists a pressure below atmospheric pressure, of means for delivering water thereto, means for adding heat to the water in said chamber in the production of low pressure steam, an ejector, a connection from said chamber to the nozzle structure of said ejector, and means for transferring heat from the fluid discharged by said ejector to said water.

71. The combination with a chamber within which there exists a pressure below atmospheric pressure, of a body of water, means for delivering water from said body into said chamber, means for transferring heat from said body to the water in said chamber in the production of low pressure steam, an ejector, a connection from said chamber to the nozzle structure of said ejector, and means for transferring heat from the fluid discharged by said ejector to said water.

72. The combination with a condenser, of an ejector for withdrawing air therefrom, a chamber within which there exists a pressure below atmospheric pressure, means for delivering condensate from said condenser to said chamber in the production of low pressure steam, a connection from said chamber to the nozzle structure of said ejector, and means for delivering heat from the discharge of said ejector into said condensate.

In testimony whereof I have hereunto affixed my signature this 29th day of March, 1922.

ROBERT SUCZEK.
